UNITED STATES PATENT OFFICE.

GRANVILLE A. HUMASON, OF HOUSTON, TEXAS, ASSIGNOR TO HUMASON ROLLER BIT COMPANY.

DRILL-BIT.

1,337,913.

Specification of Letters Patent. Patented Apr. 20, 1920.

Application filed January 24, 1919. Serial No. 272,889.

To all whom it may concern:

I, GRANVILLE A. HUMASON, a citizen of the United States, residing at Houston, in the county of Harris and 5 State of Texas, have invented certain new and useful Improvements in Drill-Bits, of which the following is a specification.

This invention relates to new and useful improvements in a drill bit, and has particular relation to that type of bit which is 10 specially adapted for use in drilling through rock, or other hard formations.

One object of the invention is to provide a bit of the character described, whose 15 lower and operative end is provided with downwardly converging cutting rollers, which, in general contour, are substantially frusto-conical in form, but which may be varied in form, as desired.

20 A further feature of the invention resides in the provision of a bit of the character described, whose cutting rollers may be readily assembled with the bit, or detached therefrom.

25 With the above and other objects in view, the invention has particular relation to certain novel features of construction, operation and arrangement of parts, an example of which is given in this specification and 30 illustrated in the accompanying drawings, wherein:

Figure 1, is a side elevation of the bit, shown partially in section along the longitudinal central line.

35 Fig. 2, is a side elevation thereof, taken at right angles to the view shown in Fig. 1, and shown partially in section along the longitudinal central line.

40 Fig. 3, is a bottom plan view, shown partially in section along a transverse central line.

Fig. 4, is a fragmentary sectional view, showing a modified form of cutting rollers.

Fig. 5, is a fragmentary sectional view, showing another form of cutting roller in elevation, and

Fig. 6, is a perspective view of the last mentioned form of roller.

Referring now more particularly to the 50 drawings wherein like numerals of reference designate similar parts in each of the figures, the numeral 1, refers to the head, which has a central opening 2, extending down through the same, and contracted at its lower end, forming the abrupt shoulder

3. The upper end of this head is reduced, forming the shank 4, which is internally threaded, thus providing for the attachment of the bit to the drill stem. Fitted through the lower reduced end of the opening 2, is the sleeve-like lining 5, whose upper end is flush with the shoulder 3, and fitted up through this lining is the spindle 6, whose lower end is formed with an annular shoulder 7, which fits against the corresponding shoulder, formed in the lower end of the head, and against which the lower end of the lining 5 rests. The lower end of the said lining has an internally threaded section, and the corresponding portion of the spindle 6 is externally threaded to engage therewith. Fitted over the upper end of the spindle, and resting upon the shoulder 3, is the washer 8, and threaded upon the upper end of said spindle, to secure the same in place, are the nut 9, and the lock nut 10. The spindle 6 may be formed integral, or of two longitudinal sections, whose flat faces fit together when assembled. In Fig. 5, the spindle is shown sectional, only one section thereof being shown. Integral with the lower end of the spindle are the downwardly diverging bearing plates 11, and 12, which diverge at approximately, a 45 degree angle with the axis of the spindle. These bearing plates are provided with openings to receive the respective bearing pins 13, which extend therethrough at approximately right angles thereto. These pins are formed integral with the lower ends of the corresponding dove tailed plates 14, which fit up into correspondingly formed grooves in opposite sides of the head. The upper ends of these plates abut against the shoulders 15, formed in the head, said shoulders serving to prevent an upward shearing strain upon the set bolts 16, by which the plates are secured against lengthwise movement, and threaded over the upper part of the head, and also of the plates is the locking ring 17, which, when threaded into position, serves to securely hold the plates in proper position. When thus secured, the lower end of this ring 17 abuts against the annular shoulders 18, which is formed by reducing the head and plates to accommodate said ring. The upper part of the ring 17 has an inwardly extending annular flange, which, when the ring is screwed into position, contacts with the annular shoulder 19 110

of the head, formed by reducing the shank 4.

The lower ends of the plates 14 are beveled outwardly, forming flat faces parallel to and spaced from the outer faces of the corresponding bearing plates 11 and 12, and the inner ends of the pins 13 are reduced, forming annular shoulders 20, which abut against the outer faces of the said bearing plates.

Surrounding the pins 13, between the beveled ends of the plates 14, and the corresponding bearing plates 11 and 12, are journals 21, forming bearings for the respective cutters 22, 22, and threaded into the respective ends of each cutter, are the ring like nuts 23 and 24, clamped between which, and the ends of the journals 21, are felt washers 25 and 26, which serve as lubricant retainers, and also exclude grit, and foreign matter from the bearings. The pins 13 project inwardly beyond the corresponding bearing plates 11 and 12, and threaded upon said projecting ends are the cup shaped journal bearings 27 which fit into corresponding recesses in the conical shaped cutters 28, and said cutters are retained on the pins by means of the ring like retaining nuts 29, which surround the pins and are threaded into said cutters, and clamped between the nuts 29, and the bearings 27, are the felt washers 28, which serve as lubricant retainers, and exclude grit and foreign matter from the bearings. If found desirable, set screws 30 may be threaded through the cutters 28, and their inner ends projected into alined annular grooves 31, around the journal bearings 27. The plates 14 are provided with downwardly extending channels 32, which extend on through the pins 13, through which a lubricant is conducted to the bearings, passing from said channels through the orifices 33 and 34. It is to be observed that before the cutters are fixed in position, the channel 32 may be filled with a lubricant, and a sufficient supply will be thus retained on hand to lubricate the cutters during the period the bit will be retained in the well before sharpening, or other repairs are required.

It will be observed that the cutters 22 are substantially cylindrical and the cutters 28 are substantially conical shaped in general contour, and having their sides corrugated or toothed, so as to readily abrade and disintegrate the formation encountered. It will be further observed from an inspection of Fig. 1, that the cutter 22 on one side is considerably longer than the corresponding cutter on the other side, and that the cutters 28 are reversely proportioned. Provision is thus made for cutting away the formation opposite the outer ends of the bearing plates 11 and 12; the cutter 22 opposite the bearing plate 11 cutting away that portion of the formation opposite said last

mentioned plate, and the cutter 28 opposite the bearing plate 12, cutting away and disintegrating that portion of the formation opposite said plate 12.

In Fig. 4, the end cutter 28' is shown rounded off, and in Figs. 5 and 6, the end cutters 28'' are shown with blunt toothed ends. In the modified forms shown in Figs. 5 and 6, the peripheries of the cutters are formed with annular cutting ribs which are spaced apart, thus in effect, forming cutting disks, which abrade away and disintegrate the formation. This modified form of cutters will be found best adapted for use in certain kinds of formation.

Substantially cylindrical side reamers 26, 26, are mounted in suitable recesses in the head. These side reamers have toothed cutting surfaces and rotate upon vertical axes, and project a short distance out beyond the head. They are preferably mounted oppositely between the boring cutters hereinabove described. These side reamers rotate upon the sleeve like journals 37, which are screwed upon the pins 38, extending axially through the reamers. At one end, each reamer is shouldered in, forming annular shoulders 39, and clamped between said shoulders and the corresponding ends of the journals 37 are the felt washers 40. Threaded into the opposite ends of the reamers, are the ring like nuts 41, and clamped between them and the corresponding ends of the journals 37, are the felt washers 42, said washers serving as lubricant retainers, and excluding the grit and foreign matter. Above the reamers are the plates 43, which fit in correspondingly shaped grooves in the head, and whose upper ends abut against the shoulders 44, formed in said head, and which prevent any shearing effect of said plates upon retaining set bolts 45, and the plates 43 are further secured in position by means of the locking ring 17, which is threaded thereover. The upper end of the pins 38 fit into corresponding recesses in the lower ends of the plates 43, and the lower ends of said pins are seated in the bearings formed in the adjoining face of the head beneath, and are retained therein by means of the detachable plugs 46, which are secured in position by means of the set screws 47. The bearings of the side reamers are lubricated by means of a lubricant previously placed in the channels 48, which extend downwardly through the plates 43, and on through the pins 38, and which turn outwardly and discharge the lubricant into the bearings through the orifices 49, provided in the journals 37.

In assembling the bit, the cutters 22 and 28 are first secured in position, and the sleeve 5 is then secured on the spindle 6. The plates 14 are then slid into their grooves, the sleeve 5 at the same time pass-

ing up into the reduced end of the opening 2, and the spindle is secured in position as hereinbefore explained. The side reamers 36 are then secured to the head, and the 5 side plates 14 and 43, are then secured in position as explained, and the bit is ready for operation. As stated, the spindle 6 may be formed of two sections in which case, the cutting rollers on each side may be se- 10 cured in position separately. This form of construction is often preferable inasmuch as it permits the removal of a cutting roller singly for repairs, or replacement. It is obvious that any of the parts of the bit may 15 be readily removed when it is desired to sharpen, repair or replace the same.

In operation, the rotation of the drill stem will cause the rotation of the drill bit attached thereto, causing the cutters 22 and 20 28 to roll on the bottom of the hole. This action, together with the weight of the stem above will cause the teeth of the cutters to grind into and disintegrate the formation at the bottom of the hole. The matter thus 25 loosened and pulverized by the cutters will be carried away by the stream of the flushing water projected downwardly through the stem, and the channels 50, and the same will be forced back upwardly through the 30 bore around the drill stem to the surface of the ground. It is clear that the formation opposite the bearing plate 11 will not be cut away by the adjacent cutter, but the opposite cutter 22 being somewhat longer 35 than the adjacent cutter 22 will disintegrate and remove said formation and likewise that portion of the formation left opposite the bearing plate 12, will be cut away and removed by the opposite cutter 28, the same 40 being made considerably longer than the adjacent cutter 28, so that the entire formation in the bottom of the hole will be gradually disintegrated and removed as the drilling progresses. Meanwhile, the side reamers 45 36 will ream out, enlarge and smooth the walls of the bore, giving a uniform hole. This form of bit is capable of sustaining a great weight inasmuch as the bearing pins 13 are sustained not only at their bases, or 50 outer ends, but also near their inner ends, by the bearing plates 11 and 12, thus permitting the use of relatively long rolling cutters which conform perfectly to the contour of the bottom of the bore, and rest 55 thereon, thus preventing a wabbling of the bit, and conduced to the steady and uniform rotation thereof.

What I claim is:

1. A device of the character described, in- 60 cluding a head, detachable plates carried by opposite sides of the head, bearing pins converging from the lower ends of said plates toward the axial center of said head, detachable diverging bearing plates carried 65 by the head and spaced from said lower

ends, and through which said pins extend, and rotatable cutters mounted on said pins on each side of the respective bearing plates.

2. A device of the character described, including a head, having a longitudinal opening therethrough, a spindle fitted into said opening and secured in the head, and whose lower end is formed into diverging bearing plates, detachable plates secured on each side of the head, spindles integral with 70 said last mentioned plates and converging downwardly toward the axial line of the head, said spindles extending through said bearing plates and rotatable cutters mounted on said respective spindles on opposite sides 75 of the corresponding bearing plates.

3. A device of the character described, including a head, having a longitudinal opening therethrough, a spindle fitted into said opening and secured in the head, and whose 80 lower end is formed into diverging bearing plates, detachable plates secured on each side of the head, a locking ring threaded over said head and plates, and securing the latter to the former, spindles fixed to said 85 last mentioned plates, and converging downwardly toward the axial line of the head, said spindles extending through said bearing plates, rotatable cutters mounted on said respective spindles on opposite sides 90 of the corresponding bearing plates.

4. A device of the character described, including a head, having a central opening, a spindle fitted into said opening and secured in the head, whose lower end is formed into 100 diverging bearings, plates fitted into grooves located on opposite sides of the head, bearing pins carried by the lower ends of said plates and converging downwardly toward the axial line of the head, said spindles ex- 105 tending through said bearings, rotatable cutters mounted on each spindle on opposite sides of the corresponding bearing, the cutter on one side being arranged in staggered relation with respect to the cutter on 110 the other side.

5. A device of the character described, including a head, having oppositely ar- 115 ranged dovetailed grooves and provided with a longitudinal central opening, a spindle fitted through said opening, and se- cured in said head, whose lower end is formed into diverging bearings, dovetailed plates fitted into said grooves, whose lower ends are spaced from the corresponding bearings, a locking ring threaded over said head and plates, spindles converging from the lower ends of said plates toward the axial center of the head and extending through said respective bearings, cutting rollers mounted on said spindles between said plates and bearings, the roller on one side being longer than the corresponding roller on the other side, and cutting rollers mounted on the inner ends of said spindles,

the lengths of which are reversely proportioned to the lengths of the corresponding cutting rollers first mentioned.

6. A device of the character described, including a head, having oppositely arranged grooves, and provided with a longitudinal central opening, a spindle fitted through said opening, and secured in said head, whose lower end is formed into diverging 10 bearings, plates fitted into said grooves, whose lower ends are spaced from the corresponding bearings, spindles converging from the lower ends of said plates toward the axial center of the head and extending 15 through said respective bearings, cutting rollers mounted on said spindles between said plates and bearings, the roller on one side being longer than the corresponding roller on the other side, cutting rollers 20 mounted on the inner ends of said spindles, the lengths of which are reversely proportioned to the lengths of the corresponding cutting rollers first mentioned.

7. A device of the character described, including a head, bearing plates at the operative end of said head, said plates being spaced apart and each diverging downwardly from the axial line of the head, a bearing pin fixed to one of said plates at 30 one end and whose other end projects through the other plate, a rotatable cutter mounted on said pin between said plates, and a rotatable cutter mounted on the projecting end of said pin.

8. A device of the character described, in-

cluding a head, oppositely disposed bearing pins carried by the operative end thereof, and converging downwardly toward the axial line of the head, a rotatable sectional cutter mounted on each pin, and detachable 40 diverging bearing plates projecting from the head and located between the sections of the respective cutters, and through which the respective pins extend, said bearing plate being detachably secured to the head.

9. In a drill bit, a head, a detachable bearing pin rigidly mounted therein, a rotatable cutter on said pin comprising two sections, one section being approximately cylindrical in shape and housed in a slot in the head, 50 the other section inclosing the end of the pin and being conical in shape and a detachable bearing plate intermediate said sections of said cutter, and through which the pin extends.

10. In a rotary boring drill, a head, a rotatable cutter mounted on a pin, inclined downwardly, toward the longitudinal axis of the head, said cutter being divided transversely into two parts, and a bearing plate 60 for said pin between the two parts of said cutter, said plates being detachable from the head, and diverging from said axis.

In testimony whereof I have signed my name to this specification in the presence 65 of two subscribing witnesses.

GRANVILLE A. HUMASON.
